FIG. 12

FIG. 10.

INVENTOR:
MATHIAS EISERLOH

UNITED STATES PATENT OFFICE

MATHIAS EISERLOH, OF CLEVELAND, OHIO

BUILDING CONSTRUCTION

Application filed January 20, 1927. Serial No. 162,301.

My invention pertains to a building construction and the method of making it and more particularly the method of assembling building units and then associating therewith

5 an induratable material in such a way as to interlock all of the initially distinct elements and obtain an integral mass of predetermined fabricated form.

I mention my familiarity with much of the prior art both practiced and patented. The latter is partially evidenced by:

10 Robinson, No. 1,150,967, of August 24, 1915.

15 Gamewell, No. 1,171,036, of February 8, 1916.

Johnson, No. 1,307,779, of June 24, 1919. Matthews, No. 1,421,278, of June 27, 1922. Brainerd, No. 1,428,470, of September 5, 1922.

20 An object of my invention is to provide a strong, light, simple, fireproof, soundproof, insulated, sanitary and economical structure. I reduce the cost of erection, especially the labor cost, by eliminating the need of any shoring and other temporary structures, such as molds or forms. Upon a suitable base foundation I erect walls comprising larger wall sections than heretofore generally used and which are preferably hollow tiles of varying hollowed divisional shape to suit conditions. The wall sections are caused to be

25 stood on end in laterally adjacent arrangement and their juxtaposed edges are formed with recesses, of any desired shape, so that in conjunction with each pair a vertical duct is provided in which reinforcing elements and later induratable material, such as concrete, may be placed. Such wall sections, if each

30 extends from floor to floor and from one beam carrying column to the next, may be more quickly assembled with fewer laborers and will gravitationally maintain their positions until after the wall has reached its desired

35 length, when the series of tiles in abutting arrangement are to be interlocked. Upon

the tops of the walls I then place preformed

40 troughs of molded material which have their bottoms supplied with openings registering

45 with the wall ducts and which have one or

both side walls fashioned with apertures for the insertion of preformed beams, the ends of which project into the troughs preparatory to being appropriately interlocked therewith. The beams are supplied along longitudinal sides with ledges so that floor slabs span the distance between parallel beams and gravitationally rest thereon. The manner of assembling permits of insertion of piping or wiring through the ducts and other passages provided prior to filling them with the interlocking concrete. If the ultimately exposed faces of the tile elements or entire wall is not to be covered, they may be ornamented in any desired manner and those surfaces of initially separate wall elements, with which concrete or plaster is to come in contact, may be roughened to improve adhesion thereto. Manifestly, my construction should be

55 70 75

stronger, will be animal and insect proof and will require no wood, except at door and window jambs or for the flooring, if desired. It will be feasible, with the aid of a crane, to have the wall elements as large as conditions warrant, say, one foot thick by four or more feet wide by nine feet high (1' x 4' x 9') in dimension.

It is to be realized that the scope of my invention comprehends many equivalent methods and constructions. The showing of the drawings and the particular description are merely specific exemplifications of a plurality of mechanical embodiments and arrangements.

80 85 90

Adverting to the drawings:

Figure 1 illustrates a typical horizontal section through a wall composed of sections having abutting edges interlocked by reinforced concrete columns.

Figure 2 is a fragmentary plan sectional view showing a modified form of wall elements adapted for inside walls.

Figure 3 is a fragmentary plan sectional view on somewhat smaller scale through a window or door jamb.

Figure 4 is a fragmentary perspective view of a trough employed at floor levels.

Figure 5 is a perspective view of a precast floor beam.

100

Figure 6 is an enlarged fragmentary vertical section showing a connection between a beam and a trough covered wall.

Figure 7 is a vertical cross-section on line 5 7-7 of Figure 6, to disclose the gravitational association with the beams, of floor slabs.

Figure 8 is a perspective view of a floor slab.

Figure 9 is a fragmentary plan view at a 10 floor level showing different stages of progressive assembly.

Figure 10 is a perspective view of a series of assembled walls and overlying troughs before the beams are placed in position and 15 before the concrete is supplied.

Figure 11 is a similar perspective view showing some of the concrete poured about positioned beam ends and with some of the floor slabs in place.

20 Figure 12 is perspective view of an imaginary skeleton of a building section as it would appear if the walls and floor were removed.

A series of duplicate wall sections 1, as 25 shown in Figure 1, are fashioned with staggered vertically extending openings 2. End edges 3 of the tiles abut and middle portions therebetween are recessed at 4. As illustrated in Figure 1, the opposed recesses 4 together define a duct or well of hexagonal cross-sectional shape, but such shape may be varied, as for instance, to be quadrangular, as indicated by the dotted lines, one of which is designated by the reference character 4^a.

30 Corner sections 5 are shown as L shaped, though their edges are similarly recessed at 4. It is to be understood, that the up-ended or erect wall sections 1 are as long as it is desired that the wall shall be high and preferably so that only one section is placed between each pair of beam supporting columns. The wall sections are positioned against each other in a laterally extending row, and the number of tiles in each horizontally extending 45 row is determined by the desired length of the particular wall. Metal reinforcing elements 6 are positioned in the vertical ducts and ultimately embedded in concrete 7 whereby to unify and interlock adjoining columns 50 of the sections.

In Figure 2 is shown a simplified modification of tiles 8 suitable for interior walls and each including a single row of openings 9 while opposed edges of the laterally abutting 55 tiles confine a smaller space 10. In Figure 3 is illustrated how the sections 1 are spaced apart at preformed windows and door jambs 11, the remote sides of which define a three sided recess 12 in opposition to the wall section recesses 4; the space defined by the recesses 4 and 12 being subsequently filled with concrete 13.

After any particular wall section has reached its desired length its upper surface 60 is mortar coated and a trough 14 permanent-

ly set thereon. The troughs include side walls 15, one or both of which, depending upon whether they are placed on outer or inner walls respectively, are provided with a series of definitely spaced apertures 16. 70 The bottoms 17 of the troughs are also provided with openings 18. The apertures 16 and openings 18 are preferably spaced together in pairs at the points on the wall where the vertical ducts are provided between adjoining stands of tiles. Preformed beams 19 are shaped to fit in the apertures 16 and reinforcing elements 20 in the beams project therefrom at each end where the extremities of the elements 20 are bent to form hooks 21. 75 The beams are also fashioned on opposite longitudinal sides with ledges 22.

It is to be understood that the beams 19 will support flooring and extend across parallel walls with their ends occupying a 80 pair of aligned apertures 16, as shown in Figures 6, 9 and 11. Floor slabs 23 are of proper length to span the distance between parallel beams so that they may be caused gravitationally to rest upon the ledges thereof, as 85 illustrated in Figures 7, 9 and 11. Each beam end may optionally be formed so that an upper division of it overhangs, as illustrated at 24 in Figure 6, thereby eventually providing a greater bearing area for the 90 floor beam. Other reinforcing rods 25, shown in Figures 6 and 11, extend longitudinally in the troughs 14 and are partially embraced by the hooks 21, as shown in Figure 6, for the purpose of providing an additional 95 interlock. Fluid concrete is then poured into the troughs 14 and into the vertical wall ducts until all become filled, as disclosed in Figure 11, whereby the base 26, wall columns, 100 troughs and beams become a unitary, substantially integral mass after induration and as suggested by the imaginary skeleton, illustrated in Figure 12, to include the base 26, the concrete columns 7, beams 19 and composite filled troughs 27.

105 The advantage of employing wall sections substantially as high as it is desired to have the distance between floors of the building and as wide as the distance between floor beam-supporting columns manifestly lies 110 with the great saving in labor cost, both by reason of requiring fewer men and less time.

I claim:

115 1. A building construction comprising the combination of a pair of spaced walls, fashioned above as a trough, the nearer walls of said troughs respectively being provided each with a pair of apertures, a pair of solid precast beams having their ends occupying said apertures respectively with its upper 120 surface flush with the tops of said troughs, said beams being fashioned with opposed relatively depressed flanges, floor slabs resting crosswise of said pair of beams upon the flanges thereof and so as to have their upper 125

- surfaces likewise flush with the upper surfaces of said beams and so as to constitute flooring capable of supporting laborers and concrete filling said troughs and level with the tops of said beams and slabs. 5
2. In a building construction, the combination of spaced walls, unitary troughs co-terminous with and affixed to the tops of said walls respectively, reinforcing rods in said troughs, the side walls of said troughs being fashioned at corresponding points with apertures open above and extending downwardly to the upper surfaces of the bottoms of said troughs, precast beams inserted in said apertures with their ends resting upon said trough bottoms and adapted to support a flooring for subsequent operations, the upper part of said beam ends being provided with projecting hooks interlocked with said rods, 10 and concrete occupying said troughs and imbedding said rods and hooks. 15
3. In a building construction, upright wall sections having upright edge surfaces shaped to form in conjunction with each other vertical ducts, troughs disposed across the tops of a plurality of said wall sections and communicating with said ducts, said troughs also provided with lateral apertures, precast beams having ends occupying said apertures, 20 a ceiling structure permanently carried by said precast beams to constitute flooring for the pouring of induratable material, and concrete filling said ducts and troughs whereby the beams and full height of the walls are 25 integrally bound together to serve as an enclosed skeleton framework. 30
4. In a building construction, upright tiles approximating in height the desired height of a room and having upright edge surfaces shaped to form in conjunction with each other vertical ducts, troughs disposed across the tops of a plurality of said tiles and having bottom openings communicating with said ducts, said troughs also provided with lateral 40 apertures located at said ducts, pre-formed beams having ends occupying said apertures and extending over said ducts, a ceiling structure permanently carried by said precast beams to constitute flooring for the pouring 45 of induratable material, and concrete filling said ducts and troughs whereby the beams and full height of the walls are integrally bound together to serve as an enclosed skeleton framework. 50
5. In combination, a pair of upstanding wall sections corresponding to the intended height of a room, opposed edges of said sections being recessed to form in conjunction with each other a vertical duct, another pair 55 of similar wall sections in a different wall, a trough structure over both walls and provided with openings registering with the said ducts and an indurated filler for said ducts and trough to bind the wall sections and walls 60 together. 65
6. In a building construction, the combination of a base, spaced walls each composed of full-height sections enclosing between their vertical edges a vertical duct, a trough resting upon and affixed to the tops of said walls respectively, the two nearest side walls and bottoms of said troughs respectively being fashioned at said ducts with apertures and openings respectively, said apertures being open above and extending to the bottom of said troughs, preformed beams inserted in the apertures with their ends resting upon said trough bottoms bordering said trough bottom holes whereby immediately to supply support for a flooring and a single mass of concrete for unifying the beams, troughs and walls with said base. 70
7. In a building construction, the combination of a base, two rows of upwardly elongated wall sections having bottoms affixed to said base and each abutting an adjacent section in its own row, the larger vertical dimension of said sections substantially corresponding to the desired height of a wall, the juxtaposed edges of the wall sections of each row being recessed to form in conjunction with each other a vertical duct, troughs resting on the tops of said rows of sections respectively and having bottom openings registering with said ducts respectively and also each having a lateral aperture, said lateral apertures being aligned with a pair of ducts in two parallel walls, reinforcing rods disposed lengthwise in said ducts and troughs, a reinforcing beam having its opposite ends occupying a pair of aligned trough apertures and with a reinforcing element projecting from its ends and an indurating filler occupying said ducts and troughs and enclosing the three crossed reinforcing elements in said duct, trough and beam and adapted in cooperation with said beam to bind the wall sections and walls together. 80
